(57) **CLAIM**

The ornamental design for a laminator, as shown and described.

DESCRIPTION

FIG. 1 is a perspective view showing the new design for a laminator;

FIG. 2 is a front view thereof;

FIG. 3 is a top view thereof;

FIG. 4 is a rear view thereof;

FIG. 5 is a bottom view thereof;

FIG. 6 is a left side view thereof, a right side view being a mirror image thereof; and,

FIG. 7 is a cross-sectional view taken along line 7-7 of FIG. 4. The broken lines in the drawings are shown for illustrative purposes only and form no part of the claimed design. In addition, the surface shading illustrated in the drawings is provided merely to highlight the contour of design; it is not intended to be illustrative of texture or gloss.
